UNITED STATES PATENT OFFICE.

ARVID BRODIN, OF LOS ANGELES, CALIFORNIA.

HAT-CROWN SHAPER.

Refiled for abandoned application Serial No. 578,133, filed July 28, 1922. This application filed December 29, 1926. Serial No. 157,852.

Heretofore in the millinery art, crown shapers of various types have been used. These have generally consisted of stiffened buckram or other material over which light fabrics have been drawn to be retained until set. The fabric from which the crown is to be formed is generally treated with some stiffening materials which when moistened with steam or other moist heat softened sufficiently to be molded or shaped to thereafter set or dry in the desired form. Various crude means have been employed to hold the material in position during the operation of shaping, which has resulted in considerable loss of time and has added to the labor required for performing the operation. The method and means employed in performing the operation have also resulted in the excess of wear and tear or destruction of the apparatus used. It is the principal purpose of the present invention to avoid this and to produce a better and more satisfactory crown, and to extend the life of the apparatus employed.

This application is a substitute for abandoned application Serial No. 578,133 filed July 28, 1922.

Drawings.

Figure 1 is a side view of a shaper constructed and arranged in accordance with the present invention.

Figure 2 is a cross section or elevation thereof showing the fabric from which the hat crown is to be constructed in the process of adjustment to the shaper.

Figure 3 is a sectional elevation showing the fabric in its final adjustment on the shaper as disposed for drying or setting thereon.

Description.

As seen in the drawings the shaper has a body portion 8 which is formed to the shape of a hat crown. Adjacent the lower edge of the side walls of the body portion are formed grooves 9 and 10. The body portion is open as seen best in Figures 2 and 3 of the drawing, the grooves 9 and 10 being juxtaposed to the edge of the opening of the said body portion.

A cushion 11 formed of fabric or other suitable material adapted to be pierced by pins or other retaining devices is permanently mounted in the groove 9. With the

shapers thus constructed the fabric 12 such as maline or similar materials having been previously treated for stiffening is drawn over the body portion 8 and preliminarily fastened as by pins 13 to the cushion 11, as seen best in Fig. 2 of the drawings. When the fabric has been thus preliminarily fastened, an elastic-band 14 is stretched upon the crown 8 and drawn downward thereover until it sinks into the groove 10, imprisoning the fabric as seen best in Fig. 3 of the drawings. While thus retained by the band 14, the material is worked down under the said band or girdle and further secured by the pins 13 to the cushion 11.

After the wrinkles have been thoroughly eradicated from the material it is permitted to dry, or the drying if desired is hastened by the dry heat admitted to the inside of the metal, or body of the shaper 8. This, however, is seldom found necessary. When the fabric has thoroughly dried or set, a suitable cutting instrument is drawn around the body 8 adjacent to the groove 10 and above the same. The shaped crown is then removed from the shaper 8 to be used in the manufacture of a hat.

The girdle or band 14 is then removed and the pins 13 being withdrawn from engagement with the cushion 11 the waste material is discarded to place the shaper in condition for the next operation.

When the material 12 is drawn tight over the ridge 15 it is drawn away from the side of the body portion 8 attaining thereby a clearance which makes it easy to remove the crown from the body.

I claim:

1. A hat crown shaper comprising a body shaped to conform to the crown of a hat and having upper and lower circumferentially extending grooves adjacent its lower end, a cushion ring in said lower groove and adapted to receive pins for temporarily retaining hat crown forming material tightly drawn upon said body, and a compression ring for fitting tightly about the crown material and body and forcing the material into the upper groove to hold the material in stretched condition.

2. A hat crown shaper comprising a body shaped to conform to the crown of a hat, a cushion extending about said body adjacent its lower end and adapted to receive pins for temporarily retaining crown form-

ing material stretched upon said body, the body being provided with a circumferentially extending seat above said cushion, and a gripping ring adapted to be engaged about said body for forcing the crown material into said seat whereby to tightly hold the material in stretched condition upon the body.

3. A hat crown shaper comprising a body shaped to conform to the crown of a hat, 10 cushion means adjacent the lower end of said body, the lower end of said body being provided with a circumferential groove therein, an outstanding annular ridge on 15 said body adjacent the upper edge of the

groove, a gripping ring adapted to be engaged over the body and seated in said groove for holding material in stretched condition on the body, said ridge acting to cause the crown material to be stretched tightly about said body at all points when said ring is positioned, and temporary securing means engageable with said cushion means for holding material stretched on said body before said ring is positioned. 25

In testimony whereof, I have signed my name to this specification this eighth day of December, 1926.

ARVID BRODIN.
